Attorneys.

UNITED STATES PATENT OFFICE.

MONTAGUE TABOR PICKSTONE, OF HAMPSTEAD, ENGLAND, ASSIGNOR TO THE
PNEUMATIC LOOM SYNDICATE LIMITED, OF BIRMINGHAM, ENGLAND.

REED FOR WEAVING-LOOMS.

1,306,189.

Specification of Letters Patent. Patented June 10, 1919.

Application filed August 28, 1917. Serial No. 188,693.

To all whom it may concern:

Be it known that I, MONTAGUE TABOR PICKSTONE, of 64 Alexandra road, Hampstead, in the county of Middlesex, England, have 5 invented certain new and useful Improvements in Reeds for Weaving-Looms, of which the following is a specification.

This invention relates to weaving looms in which the shuttle is operated pneumatically 10 and the chief object of the present invention is to provide an improved reed which will guide the shuttle positively as it traverses across the width of the loom from shuttle box to shuttle box.

15 The invention comprises a reed the members of which are so formed or shaped as to provide a race from which the shuttle is prevented from escaping otherwise than longitudinally, the reed plates, which constitute the reed, being undercut at the ends 20 to engage with similar grooves in the supporting rails.

The accompanying drawing shows in cross section a reed constructed according to this 25 invention, the reed being shown employed in a loom in which the warp threads ascend in an approximately vertical line from the beam to the fell of the cloth. With reeds of the type indicated a shuttle of tubular 30 form is employed as indicated at A. The reed is made up of a number of metal plates B. The members B have crescent shaped holes or cut-out portions formed in them centrally providing the horns or inward projections B', B'. The distance between the horns B', B' is less than the diameter of the shuttle, so that the latter can only move longitudinally in the race. The warp threads— 35 shown in an open-shed position—are indicated at W the heddle eyes at H and the fell of the cloth at D. The reed members B are held in position by two grooved rails C; the ends B² of the reed members B are dovetailed to fit into the groove C' of C as

shown. With this type of reed the ordinary 45 shuttle race provided by the upper face of the slay is dispensed with.

It is already shown by my prior specifications of British Patents No. 4507 of 1909 and No. 14758 of 1911 to employ reed plates 50 with central U-shaped slots in them for the shuttle. These reed plates do not prevent the shuttle rising out of the groove, and plates are threaded upon side supporting rods. 55

What I claim as my invention and desire to protect by Letters Patent is:—

1. In a loom, a combined shuttle race and reed adapted to guide the shuttle positively as it travels across the loom, comprising a 60 plurality of reed plates arranged parallel to each other having crescent shaped holes formed in them to secure the shuttle and prevent its escape otherwise than longitudinally while their ends are undercut to engage with undercut grooves in supporting rails. 65

2. A reed for weaving looms comprising a plurality of reed plates mounted parallel to each other, the plates each having a cut out 70 portion alined with the adjacent plates to form a race for guiding the shuttle positively across the loom, and means also provided by said cut out portions for preventing escape of the shuttle from the race laterally thereof. 75

3. A reed for weaving looms, comprising a plurality of reed plates mounted substantially parallel to each other, each plate having a crescent shaped cut-out portion in 80 one edge thereof providing inward projections at said edge of the plate, said cut-out portions being alined to form a shuttle race, the distance between said projections being less than the greatest diameter of the race. 85

In testimony whereof I have affixed my signature.

MONTAGUE TABOR PICKSTONE.
